[57] CLAIM

The ornamental design for a car cover with a checkerboard pattern, as shown and described herein.

DESCRIPTION

FIG. 1 is a side view of a car cover with a checkerboard pattern in accordance with a preferred embodiment of the present invention, with the opposing side view being the same;

FIG. 2 is a front view of the cover of FIG. 1, with the differing sizes of the checkerboards varying with the inclination of the pattern relative to an observer's viewpoint;

FIG. 3 is a rear view of the cover of FIG. 1; and,

FIG. 4 is a top view of the cover of FIG. 1;

The broken line showing of environment is for illustrative purposes only and forms no part of the claimed design.
